OPERATING HANDLE INTERLOCK AND IMPULSE TRANSMISSION SWITCH ASSEMBLY FOR RACE TOTALIZATORS

Awdry Francis Julius, Sydney, New South Wales, Australia, and George Alfred Julius, deceased, late of Sydney, New South Wales, Australia, by Eva Dronghsia Odierna Julius, Killara, near Sydney, New South Wales, Australia, and Awdry Francis Julius and Russell Stuart Hicks, Sydney, New South Wales, Australia, executors, assignors to Automatic Totalisators, Limited, Sydney, New South Wales, Australia

Application June 30, 1948, Serial No. 36,163
In Australia June 30, 1947

10 Claims. (Cl. 235—91)

1

This invention is referable to race totalisator ticket issuers of the general type broadly classifiable as incorporating an operating handpiece which on suitable manipulation relative to a dial plate, carrying numbers or numbered holes (for registration therewith of a pointer or pin on the handpiece) respectively corresponding to a number of race competitors, causes a selector switch or brush finger to contact a corresponding selector contact button, and also causes an "interlock" switch to be closed, whereby an "integrator" circuit for a competitor adding unit is energised; thus, by transmission of an electrical impulse to the competitor adding unit, to record a ticket issuing transaction relative to that competitor. In addition to being instrumental in the recording of each transaction as indicated above, operation of the handpiece also conditions printing or type devices in readiness for printing the ticket which is required to be characteristic of and peculiar to the particular transaction. Operation of the handpiece also actuates mechanical interlock means for locking the handpiece against further manipulation, and holding the interlock switch closed, until the ticket printing cycle is irrevocably in course of completion. The integrator circuit includes a trip coil or solenoid which on closure of the circuit is energised to operate a trip switch whereby the integrator circuit is then opened and the circuit of a magnetic clutch is closed. This clutch is associated with the drive shaft of a continuously running motor. Closure of the clutch circuit, and consequent drive through the clutch, causes rotation (through worm or other gearing) of a cam shaft, which on completion of a single revolution is halted by automatic opening of the clutch circuit.

A revolution of the mentioned cam-shaft (working through the agency of suitable gearing, cam-followers, bell-cranks, links, levers, or the like) operates:

(a) A platen or backing pad whereby a ticket portion of a ticket strip or roll is pressed for printing towards the previously conditioned type devices, an inked ribbon being disposed between the type and the ticket face to be printed.

(b) Friction grip feed rolls or like devices whereby a strip or ribbon of ticket paper is fed through a feed chute, and into and through a ticket printing station.

(c) The inked ribbon is "inched" or traversed

2

a short distance through the printing station by turning a winding reel therefor; and,

(d) A guillotine blade or scissors is operated to cut the just printed ticket portion from the ticket strip.

"Veeder" or other counting mechanism may also be operated as a direct, or indirect, result of the cam shaft revolution to record a total printed ticket output of the issuer.

- 10 Immediately following the printing and issue of a ticket due to near completion of a single revolution of the cam shaft, the mechanical interlock for the selector handpiece is released in readiness for re-operation thereof, and the 15 interlock switch (which ceased to be alive when the trip switch opened the integrator circuit) is re-opened. Directly after this re-opening of the interlock switch, another cam reverts the trip switch into the integrator circuit thus 20 opening the magnetic clutch or "issuer" circuit and thereby conditioning the issuer as a whole for a next ticket issue transaction.

The present invention is primarily directed to what may be called "the operating handle 25 interlock and impulse transmission switch assembly" or, more shortly, "the interlock unit" for a ticket issuer of the general type above indicated. Such a unit comprises those parts whereby a depressed operating handpiece is locked in depressed position until the ticket issuing transaction is finished, the mentioned interlock and trip switches, means for manually releasing the handpiece lock as and when required, and the several levers, cams, springs, magnets and the like for the necessary interaction and interoperation of those parts.

Interlock units as devised heretofore are imperfect in two major respects. First, in regard to the means for manual release of the handpiece interlock; and, second, the inability for a 40 number of issuers each issuing tickets of widely varying values to feed impulses to a single adding unit without requiring what in many cases is unnecessary complication in the design of the adding unit.

45 Manual release of the handpiece interlock is mainly required when a selector mis-dialling is made by the issuer operative, by having depressed the handpiece in respect of a dial number in respect of which there is no competitor. 50 For example, when a competitor has been "scratched" from a race.

To prevent issue of tickets in respect of

scratched competitors, the integrator circuit for that competitor is caused to remain open, during the ticket selling period for the particular event, by the opening of control switches, in the main control room for the whole totalisator installation. It follows from this that when depression of a handpiece relative to a scratched competitor is effected, the issuer will not operate; but, the handpiece having been depressed is caught by its interlock, and, for the time being, cannot be released for further ticket selling. To meet this difficulty it has been proposed to provide a push button within reach of the issuer operative, which on being depressed trips the interlock to release the handpiece for further use. This expedient has the fault that although it enables rapid interlock release when a mis-dialling in respect of a dead integrator circuit has occurred, it also enables the operative to open the interlock when it should not be opened, and this can be gravely inconvenient or even damaging to the equipment.

As a remedy for the fault, just referred to, it has been further proposed to provide an interlock releaser which may only be operated with a special key, this key being given only to a responsible person such as the mechanic in charge of a battery of issuers. This practice practically eliminates errors but causes grave delay, because, when the mis-dialling has occurred, the operative has to inform the mechanic and wait for him to effect the release.

Reverting to the second imperfection, referred to above, in existing interlock units; the mentioned trip switch is usually operated by the rocker armature of an electromagnet (herein called a "trip" magnet) in the integrator circuit. This magnet being in series with escapement magnets on the adding units so that the completion of the integrator circuit operates the escapement magnet on the appropriate competitor adding unit and on the appropriate grand total adding unit and, at the same time, operates the issuer trip switch, so that a ticket is then printed to correspond with the transaction which has been recorded in the adding units. To provide for tickets of varying values (for example, one monetary unit, two units, four units, and so on), the issuers are connected (through their trip magnets and the adding unit magnets) to adding unit escapement wheels with different numbers of teeth. For example, the single unit issuer would be connected to a forty tooth escapement wheel; and, a two unit issuer would be connected to a twenty tooth escapement wheel, so that the issue of a two unit ticket will allow the integrator in the adding unit to move twice as far as for a single unit ticket, and so on.

The integrators are made up with one or more escapement shafts, each of which has up to six escapement wheels thereon. The number of escapement shafts depends on the size of the installation and the number of ticket issuers required. In most installations an extensive range of ticket values is required—say, from one unit up to twenty units. This is to say, the maximum ticket value is twenty times a minimum ticket value.

On any one escapement shaft it is not possible to have escapement wheels to provide for this wide range of values, as forty teeth is the maximum practical number which can be used, and a twenty unit issuer would therefore require an escapement wheel with only two teeth, which is

not practicable, as the minimum number of teeth which can be satisfactorily operated is five.

It has not been practicable, therefore, to provide issuers for the sale of single unit and twenty unit tickets in relation to a single adding unit escapement shaft, and, where this range of values is required it has been necessary to use two or more escapement shafts in each adding unit, the lower value issuers being connected to one escapement shaft and the higher value issuers to another. This is not particularly detrimental where the totalisator installation is a large one which of necessity requires more than one escapement shaft, but it is a serious disadvantage in the case of a small installation which could be accommodated with one escapement shaft except for the fact that the range of ticket values is too great.

The object of the present invention is to overcome the mentioned shortcomings in a simple manner, by the provision of an interlock unit in a ticket issuer wherein; an interlock release is provided which may be used by an operative only when a mis-dialling, in respect of a dial plate position for which there is no competitor, has occurred, and is inoperative when misused; and wherein by simple modification of the unit it may be employed for issue of tickets of any selected high value, in conjunction with other issuers for tickets of any selected low or other values, in connection with standard adding units containing only one escapement shaft.

In the following description, the nature of the present invention is set forth with reference to certain known elements in and relating to a ticket issuer; but description of known elements is introduced only insofar as it is necessary clearly to describe the invention and the parts necessary for carrying it into practical effect.

The invention may be summarised as primarily consisting in an interlock unit for a race totalisator ticket issuer, comprising, an interlock lever able to assume either a "locking" position or an "unlocking" position, loading devices which influence the interlock lever to assume and remain in its locking position, means operable on depression of the ticket issuer handpiece to allow the interlock lever to assume its locking position and thereby hold the handpiece depressed, a thrust rod which is movable towards the interlock lever (but is unable to bear directly thereon) a movable packing member, able to assume a "working" position directly between the thrust rod and the interlock lever, an interlock switch which is closed by the interlock lever when in its locking position, and electrically operable means which on closure of the interlock switch and contingently upon current flow therethrough displace the packing member from its working position, revert the interlock lever to its unlocking position, and then revert the packing member to its working position.

An example of the invention is illustrated by the drawings herewith.

Figure 1 is a side elevation of an interlock unit. Figure 2 is a side elevation of the interlock unit shown in Figure 1 but looking on the reverse side of the unit.

Figure 3 is a plan projected from Figure 2.

Figure 4 is a schematic perspective view showing the main working parts of the unit shown in Figures 1 to 3.

Figure 5 is a similar view to Figure 2 illustrating a modification.

Figure 6 is a sectional elevation taken sub-

stantially along line 6—6 in Figure 5 (or Figure 7).

Figure 7 is a sectional elevation taken substantially on the plane indicated by line 7—7 in Figure 6.

Figure 8 is a plan projected from Figure 5.

Figure 9 is a circuit diagram showing the electrical arrangements for the interlock units illustrated by Figures 1 to 8 and parts co-operative therewith.

Referring mainly to Figures 1 to 4, the handpiece 10 (Figure 4) of a ticket issuer of the kind briefly identified herein, has a dropper 11 depending therefrom. When the handpiece is depressed in initiation of a ticket issue cycle, the dropper is lowered. The dropper has one arm 12 of an initial lever pivotally coupled thereto. The initial lever is preferably in the form of a bell crank 13 which is fulcrumed at 14, on the interlock unit frame 15. This frame is mounted on the ticket issuer chassis or base indicated by 16. The second arm 17 of the bell crank projects upwardly, and the end face 18 of this second arm has an interlock step 19 formed therein.

An interlock lever 20 is fulcrumed on a pin 21 mounted on the unit frame 15. This lever is preferably three-armed as shown. One arm 22 of the lever is adapted to rest upon the upper end face, or the stepped portion of the upper end face, of the second arm 17 of the initial lever 13, thus defining the unlocking position of the interlock lever. The second arm 23 of the interlock lever has a cam-follower block 24 and an abutment peg 25 thereon. The follower block lies in the path of a release cam 26 which is keyed on the issuer main drive shaft 27 (that is, the shaft adapted to be driven through the magnetic clutch of the issuer). When the interlock lever moves into its locking position, in which the end of arm 22 is resting on the step 19 (instead of the end face 18) the peg 25 bears against a spring contact arm 28 forming one leg of the interlock switch 29, and thus closes that switch. The third arm 30 of the interlock lever has its outer end portion aligned below a push-rod 31. The interlock lever is furnished with a loading spring 32, the effect whereof is to influence the lever to assume or remain in its locking position; that is, with its first arm 22 bearing firmly against the step 19.

The push rod 31 carries a press button 33 which is finger accessible to the issuer operative, through a hole 34 in the issuer cover plate 35. The push rod is mounted for endwise movement in a suitable bracket, such as 36, and is equipped with a spring 37 which at all times influences the push rod to assume or remain in its fully raised position. The range of movement of which the push rod is capable is such that at no time is it able to bear directly upon the third arm 30 of the interlock lever. When push rod pressure is required upon the third arm it may only take place through the agency of a movable packing member 38, when that member is positioned directly between the third arm and the adjacent end of the push rod. The operation of this packing member will be dealt with later herein.

When the handpiece dropper 11 is lowered, to start a ticket issue cycle, the initiating lever 13 is turned through a few degrees so that the first arm 22 of the spring-loaded interlock lever, instead of resting on the top end surface 18 of bell-crank arm 17, slips on to the lower level of what may be called the "tread" surface of the step 19. Because of this, return movement of

the bell-crank is now prevented by reason of the "riser" surface (39) of the step being abutted with the end face of the arm 22, and hence the issuer handpiece is locked in its depressed position, and is therefore immovable, until the interlock lever is later moved to lift its arm 22 clear of the step 19.

The initial turn of the interlock lever closes the interlock switch 29 and thus completes the integrator circuit for recording the transaction in respect of which a ticket is in course of production.

The integrator circuit includes a pair of contacts 40 in the trip switch 41. These "integrator" contacts are, at this stage of the cycle, held closed by a peg 42 on a trip lever 43 (referred to more fully later herein). The trip lever is fulcrumed on pin 21, and peg 42 bears against a spring leg 44 on which one of the integrator contacts is carried.

Closure of the integrator circuit energises the trip magnet 45. This turns a rocker lever 46 (through a few degrees) which is in armature relation to the magnet. This turning of the rocker lever is effected in opposition to the influence of a loading spring 47. The rocker lever has an end face step 48. While the rocker lever is unattracted by the trip magnet, the trip lever (due to the influence of loading spring 49) bears against the outermost end face 50 of the rocker lever and thus holds the contacts 40 closed. When the trip magnet attracts the rocker lever 46 the trip lever slips on to the tread step 48, thus causing the peg 42 to leave the integrator contacts 40 which then move apart to open the integrator circuit and hence deenergise the trip magnet. In this movement the peg 42 moves against the spring leg 51 of a pair of "issuer" contacts 52 forming part of the trip switch. Closure of the issuer contacts completes the magnetic clutch circuit whereby the printed ticket production side of the issuer cycle is carried out.

From the foregoing it will be seen that the trip lever has two significant positions, one (which may be called its "integrator" position) in which the integrator contacts 40 are held closed, and one (its "issuer" position) in which the issuer contacts 52 are closed.

As previously stated, closure of the clutch circuit results in a single revolution of the main drive shaft 27. This shaft carries the first release cam 26, and a second release cam 53 which similarly co-operates with a second follower block 54 on the trip lever 43.

The trip lever has a striker limb 55 thereon which bears against the tail 56 of a "packing" lever, which on its other arm 57 carries the packing member 38. The packing member may be in the form of a roller able to run on the upper surface of the interlock lever arm 30. The packing lever is secured on a fulcrum bush 58 which is rotatable to enable running of the packing member on the interlock lever but is loaded by a spring 59 so that it keeps the tail 56 against the striker limb 55.

The rectangle 60 (see Figure 9) and the matters therein represent a ticket issuer. Each issuer in the totalisator installation is respectively connected to a contact (such as 61) of a distributor switch having a constantly rotatable contact arm 62. The purpose of the distributor switch is to ensure that only one issuer is alive at any one time. The distributor is connected to a grand total adding unit 63. The competitor selector

contacts (1, 2, 3, . . .) of the several issuers are respectively connected to the competitor adding units (64, 65, 66 . . .). Each competitor adding unit circuit is completed by way of a control switch (67, 68, 69 . . .). These switches are located in the control room for the entire installation. They are all closed during normal operation excepting these corresponding to competitor adding units not to be used. For example, if competitor No. 2 is scratched, then control switch 10 68 is left open, so that adding unit 65 is dead and the No. 2 selector contacts in all the ticket issuers are also dead.

When a transaction is to be recorded, and a ticket issued therefor, (in respect of competitor 15 No. 1, for example) the handpiece 10 (of any one of the issuers) is turned to No. 1 on its dial plate, so that the selector brush finger 70 (Figure 9) is similarly brought to No. 1 selector contact. Control switch 67 has previously been closed in 20 the control room. The integrator contacts 40 are, at this stage, still closed. The handpiece is then depressed. This action, operating through the dropper 11, turns the initial lever 13 through a few degrees, so that arm 22 of the spring-loaded interlock lever slips on to the step 19 and thus 25 the handpiece is (for the time being) held immovable in its depressed position. The slip motion of the interlock lever closes the interlock switch 29 through the agency of peg 25. The integrator 30 circuit is thus conditioned to record a transaction for No. 1 competitor, and completion of the circuit occurs when the distributor arm 62 reaches contact 61. Completion of the integrator circuit sends an impulse through the grand total adding 35 unit 63 and the competitor adding unit 64, thus to record the transaction in both places.

Completion of the integrator circuit also energises the trip magnet 45. This actuates the 40 rocker lever 46 so that the spring-loaded trip lever slips from end face 50 into the step 48. This movement of the trip lever causes its striker limb 55 to recede from the tailpiece 56, thus allowing the spring 59 to move the packing member 38 from between the push rod 31 and the third arm 30 of the interlock lever. Under these circumstances of normal transaction recording, the push rod is thus rendered ineffective and consequently pressure on the button 33 will not affect the interlock because the push rod cannot reach it. This means that (for the time being) the push rod cannot be used for releasing the handpiece 45 interlock.

The movement of the trip lever responsive to energisation of the trip magnet, causes the peg 55 42 to recede from the trip switch leg 44 and then bear against leg 51, thus separating the integrator contacts 40 and closing the issuer contacts 52. Separation of contacts 40 re-opens the integrator circuit. Meeting of contacts 52 closes the issuer 50 circuit and thus commences the ticket printing and issuing cycle.

Closure of the issuer circuit energises a magnetic clutch 71 (Figure 9) which causes the drive shaft 27 to commence turning. When this turning is about equal to half a revolution the first release cam 26 engages the follower block 24 thus to revert the interlock lever to its unlocking position shown in Figure 1. This re-opens the interlock switch 29 and releases the initial lever 13 70 so that the issuer handpiece is freed (for subsequent operation) by its usual loading spring (not shown) unless, of course, it is deliberately held depressed because another transaction the same as that nearing completion is to be handled.

When the shaft 27 has turned through an angle nearly equal to one revolution, the second release cam 53 engages the trip lever follower block 54, thus (a) separating the issuer contacts 52 to de-energise the magnetic clutch and thereby halt shaft 27 (b) reclosing the integrator contacts 40 in readiness for a next transaction cycle, (c) allowing the rocker lever 46 to re-assume its position shown in Figure 2 thereby to hold the integrator contacts closed, and (d) causing the striker limb 55, by bearing against the tailpiece 56, to bring the packing member 38 back into position directly between the push rod 31 and the third arm 30 of the interlock lever.

As the shaft 27 executes a single revolution for each transaction, it may be employed to operate a transaction counter by way of (for example) a heart shaped cam 72, which is fixed on the shaft, and a follower lever 73 fulcumed on pin 21.

When an adding unit circuit is dead, because a control switch such as 68 is open, the trip magnet 45 remains dead notwithstanding the fact that the interlock switch 29 and the integrator contacts 40 are closed, and therefore the rocker lever 46 is not operated. Consequently the trip lever is similarly not operated. This means that the striker limb 55 does not cause any movement of the packing member 38, which therefore remains in its usual position of direct alignment between the push rod 31 and the third arm 30 of the interlock lever. Under these circumstances finger pressure on the push rod, acting through the interposed packing member, will bear upon and depress the third arm of the interlock lever, thus releasing the handpiece interlock.

In the interlock unit as described above it will be recalled that for each transaction there is a single closure of an integrator circuit for each operation of a competitor adding unit. This is immediately followed by an issuer circuit closure for production of a ticket characteristic of the transaction. It will thus be appreciated that where it is required to use an issuer for the production of high value tickets which are to be recorded in an adding unit by way of an escapement shaft also having small value transactions fed thereto from other issuers, it will only be necessary for the integrator circuit of the high value ticket issuer to be closed and re-opened some selected plural number of times for each single closure of its issuer circuit, for the high value transactions to be readily handled by the adding unit escapement shaft, simply by the use of an escapement wheel thereon, wherein the number of teeth (say two teeth) which would otherwise be necessary for the integration of the high value transaction is multiplied by the selected plural number referred to above.

To carry out this function (plural closure of integrator circuit for each single closure of issuer circuit) it is only necessary to defer closure of the issuer contacts 52 until such time as the requisite number of separate impulses have been sent through the integrator circuit. It follows, that postponement of the closure of contacts 52 may be effected by deferring actuation of the trip lever, and to do that it is necessary to alter the above described arrangement in which the trip lever is actuated in direct response to every energisation of the trip magnet (which is energised by each integrator impulse) by rendering each single actuation of the trip lever responsive to the selected plural number of trip magnet

energisations. Simple means to this end are readily capable of incorporation in the interlock unit subject hereof.

These means comprise a "multi-impulse" switch which is normally closed, and is opened and re-closed for each energisation of the trip magnet, and cam and follower devices which as a result of a selected plural number of multi-impulse switch openings and re-closures, operates the trip lever (as already described herein) to then open the integrator contacts 40 and close the issuer contacts 52.

The multi-impulse switch 74 is indicated diagrammatically in Figure 9. It may be connected across any two convenient points in the integrator circuit as indicated by lines 75 in that figure. When the multi-impulse switch is connected in the integrator circuit, that circuit is, of course, broken between the points of connection (that is to say, it is not left intact between the connection points as shown in Figure 9).

Referring to Figures 5 to 9, the trip magnet 45 has an escapement rocker lever 76 in armature association therewith. This lever is loaded by tension spring 77 and has two escapement stops 78 thereon. These stops are engageable in known manner with the teeth of an escapement wheel 79 which is freely mounted on the issuer main drive shaft 27. Escapement wheel 79 has the selected plural number (say five) of teeth thereon, in correspondence with the plurality of integrator circuit closures required to each issuer circuit closure.

The multi-impulse switch 74 has two contacts 80. These contacts are mounted on spring arms, one of which (81) is movable for closure or separation of contacts 80. The spring setting of arm 81 is such that it always tends to keep the contacts separated. Arm 81 may be pressed against for closure of contacts 80, directly by the teeth of escapement wheel 79, but for preference, closures of contacts 80 are effected by a cam 82 having the same number of throws (83) as the escapement wheel has teeth. The multi-impulse cam 82 is fixed to the escapement wheel, and is so phased relative thereto that whenever the escapement wheel is held (by one of its teeth) by the rocker lever 76, as shown in Figure 5, one of the cam throws 83 is bearing against arm 81 to hold the contacts 80 closed. Thus, contacts 80 are normally closed. The escapement wheel is, of course, constantly urged to rotate (in the direction of arrow 84—Figure 5) by a conventional motor spring, such as 85 (Figure 8), the rewinding of which is referred to later herein.

Escapement wheel 79 and multi-impulse cam 82 have a single throw cam 86 fixed relative thereto. A follower lever 87 (of cam 86) is fulcrumed at 88, and is loaded by spring 89 to keep in touch with cam 86. This cam has a step 90 which is able to co-act with the trip lever 43 in the same manner as the step 48 of rocker lever 46 (Figures 2 and 4).

When a high value transaction is to be recorded (as a plurality of lower value transactions) and a single ticket issued therefor, through the agency of the interlock unit illustrated by Figures 5 to 8; the integrator circuit is completed (except that it may be waiting for final closure by the distributor switch 62) by closure of the interlock switch 29 as already described herein. At this stage the integrator contacts 40, and the related control switch such as

67 are already closed as previously explained, and the multi-impulse switch 74 is similarly pre-closed by reason of the cam 82 having one of its teeth 83 bearing against the spring arm 81.

5 Closure of the integrator circuit energises the trip magnet so that the escapement pawl is activated to allow the spring driven escapement wheel to start turning through one tooth space. In doing this the resulting movement of cam 82 10 causes the switch 74 to open, thereby breaking the integrator circuit, and thus de-energising the trip magnet. This releases the spring-loaded rocker lever 76 which then allows the escapement wheel to complete its turn through one tooth space. 15 This causes re-closure of the switch 74 and the process is thus repeated. Each time the integrator circuit and hence the trip magnet is energised, the escapement magnet on the competitor adding unit is similarly energised, 20 and thus for each circuit closure a transaction (which is a selected fraction of the full high value transaction for which a ticket is to be issued) is recorded.

Again, assuming that the escapement wheel 25 has five teeth so that five competitor adding unit impulses are given for the issue of one ticket; as the escapement wheel passes through its fifth tooth space turn the single throw cam 86 operates the cam follower lever 87, which in turn 30 trips the trip lever 43. This opens the integrator circuit and closes the issuer circuit, and so starts the issuer printing the ticket. As the contacts 40 will have been opened by this action the trip magnet will not then be energised when the 35 switch 74 is reclosed and thus there will be no further operation of the trip magnet until the issuer has printed the ticket and the trip lever has been reset by its cam 53 in the same manner as previously described herein. The motion of 40 cam 53 is due to the turning of shaft 27, and this shaft movement is employed to rewind the motor spring 85.

It will be seen that for each one-fifth part (or 45 other selected fraction) of each transaction, the multi-impulse switch 74 is first opened and then re-closed, and will remain closed until the trip magnet 45 is again energised. This re-energisation of the magnet is, of course, contingent upon the distributor switch 62 making with the appropriate contact such as 61. In order to save time 50 in waiting for distributor switch operation (and bearing in mind that, as a rule, only a few ticket issuers would be required for production of high value tickets) each ticket issuer may be connected to more than one of the distributor contacts, provided, of course, that no contact (such as 61) is made common to a plurality of issuers.

What we claim is:

1. An interlock unit for a race totalisator ticket issuer, comprising, an interlock lever able to assume either a locking position or an unlock position, a biasing spring which influences said interlock lever to assume and remain in its locking position, a ticket issuer hand piece 60 means operable on depression of the ticket issuer handpiece to allow said interlock lever to assume its locking position and thereby hold said handpiece depressed, a thrust rod which is movable towards said interlock lever, a movable packing 65 member, spring biasing means to move said packing member to assume a working position directly between said thrust rod and said interlock lever, an interlock switch which is closed by said interlock lever when in its locking position, 70 and electrically operable means which on closure 75

of said interlock switch and contingently upon current flow therethrough releases said spring biasing means to displace said packing member from its working position, and separate means controlled by said electrically operable means to revert said interlock lever to its unlocking position, and then revert said packing member to its working position.

2. An interlock unit for a race totalisator ticket issuer, comprising, an interlock lever able to assume either a locking position or an unlocking position, a biasing spring which influences said interlock lever to assume and remain in its locking position, a ticket issuer hand piece means operable on depression of the ticket issuer hand piece to allow said interlock lever to assume its locking position and thereby hold said handpiece depressed, a thrust rod which is movable towards said interlock lever, a movable packing member spring biased to assume a working position directly between said thrust rod and said interlock lever, a lever having said packing member mounted thereon, a trip lever able to assume either an integrator position or an issuer position, biasing means which influence said trip lever to assume and remain in its issuer position, means for keeping said packing member lever in touch with said trip lever, an interlock switch which is closed by said interlock lever when in its locking position, and electrically operable latch means which on closure of said interlock switch and contingently upon current flow therethrough, allow said biasing means to move said trip lever into its issuer position, and separate electrical means controlled by said electrically operable latch means to revert said interlock lever to its unlocking position, and then revert said trip lever to its integrator position.

3. An interlock unit for a race totalisator ticket issuer, comprising, an interlock lever able to assume either a locking position or an unlocking position, a biasing spring which influences said interlock lever to assume and remain in its locking position, a ticket issuer hand piece means operable on depression of the ticket issuer hand piece to allow said interlock lever to assume its locking position and thereby hold said handpiece depressed, a thrust rod which is movable towards said interlock lever, a movable packing member able to assume a working position directly between said thrust rod and said interlock lever, a lever having said packing member mounted thereon, a trip lever able to assume either an integrator position or an issuer position, biasing means which influence said trip lever to assume and remain in its issuer position, means for keeping said packing member lever in touch with said trip lever, an interlock switch which is closed by said interlock lever when in its locking position, a trip magnet in series with said interlock switch, a spring-loaded rock lever which is in armature relation to said trip magnet and is engageable with said trip lever to define the integrator and issuer positions thereof, a pair of self-opening integrator contacts which are in series with said interlock switch and are closed by said trip lever when in its integrator position, a pair of self-opening issuer contacts which are closed by said trip lever when in its issuer position, and cam and follower devices which on closure of said issuer contacts consequent upon energisation of said trip magnet are able to place said interlock lever in its unlocking position and then place said trip lever in its integrator position.

4. An interlock unit for a race totalisator

ticket issuer, comprising, an interlock lever able to assume either a locking position or an unlocking position, spring biasing means which influence said interlock lever to assume and remain in its locking position, an initiating lever engageable with said interlock lever to define the locking and unlocking positions thereof, a ticket issuer hand piece, a dropper connected to said initiating lever and to the ticket issuer handpiece, a thrust rod which is movable towards said interlock lever, a movable packing member able to assume a working position directly between said thrust rod and said interlock lever, an interlock switch which is closed by said interlock lever when in its locking position, and electrically operable means which on closure of said interlock switch and contingently upon current flow therethrough releases said spring biasing means to displace said packing member from its working position, and separate means controlled by said electrically operable means to revert said interlock lever to its unlocking position, and then revert said packing member to its working position.

5. An interlock unit for a race totalisator ticket issuer, comprising, an interlock lever able to assume either a locking position or an unlocking position, a biasing spring which influences said interlock lever to assume and remain in its locking position, an initiating lever engageable with said interlock lever to define the locking and unlocking positions thereof, a ticket issuer hand piece, a dropper connected to said initiating lever and to the ticket issuer handpiece, a thrust rod which is movable towards said interlock lever, a movable packing member able to assume a working position directly between said thrust rod and said interlock lever, a lever having said packing member mounted thereon, a trip lever able to assume either an integrator position or an issuer position, spring biasing means which influence said trip lever to assume and remain in its issuer position, spring biasing means for keeping said packing member lever in touch with said trip lever, an interlock switch which is closed by said interlock lever when in its locking position, and electrically operable latch means which on closure of said interlock switch and contingently upon current flow therethrough, allows said trip lever to move into its issuer position under the influence of said spring biasing means, and separate means controlled by said electrically operable latch means to revert said interlock lever to its unlocking position, and then revert said trip lever to its integrator position.

6. An interlock unit for a race totalisator ticket issuer, comprising, an interlock lever able to assume either a locking position or an unlocking position, spring biasing means which influence said interlock lever to assume and remain in its locking position, an initiating lever engageable with said interlock lever to define the locking and unlocking positions thereof, a ticket issuer hand piece, a dropper connected to said initiating lever and to the ticket issuer handpiece, a thrust rod which is movable towards said interlock lever, a movable packing member able to assume a working position directly between said thrust rod and said interlock lever, a lever having said packing member mounted thereon, a trip lever able to assume either an integrator position or an issuer position, spring biasing means which influence said trip lever to assume and remain in its issuer position, spring biasing means for keeping said packing member lever in touch with said trip lever, an interlock switch which is closed by said

interlock lever when in its locking position, a trip magnet in series with said interlock switch, a spring-biased rocker lever which is in armature relation to said trip magnet and is engageable with said trip lever to define the integrator and issuer positions thereof, a pair of self-opening integrator contacts which are in series with said interlock switch and are closed by said trip lever when in its integrator position, a pair of self-opening issuer contacts which are closed by said trip lever when in its issuer position, and cam and follower devices which on closure of said issuer contacts consequent upon energisation of said trip magnet are able to place said interlock lever in its unlocking position and then place said trip lever in its integrator position.

7. An interlock unit for a race totalisator ticket issuer, comprising, an interlock lever, a biasing spring for said interlock lever, an initiating lever having a ticket issuer hand piece stepped portion engageable with said interlock lever, a dropper connected to said initial lever and to the ticket issuer handpiece, a spring-biased thrust rod movable towards said interlock lever, a packing member able to lie between said thrust rod and said interlock lever, a spring-biased lever whereon said packing member is mounted, an interlock switch closable by said interlock lever, a trip magnet connected in series with said interlock switch, a spring-biased rocker lever in armature relationship with said magnet, a spring-biased trip lever engageable with a stepped portion of said rocker lever and with said packing member lever, a pair of integrator contacts in series with said interlock switch and a pair of issuer contacts alternatively closable by said trip lever, two follower blocks respectively mounted on said interlock lever and said trip lever, two release cams respectively associated with said follower blocks, and means operable in response to closure of said issuer contacts for turning said release cams.

8. An interlock unit according to claim 2 wherein said electrically operable means include a multi-impulse switch in series with said interlock switch, and means enabling repetitive opening and closing of said multi-impulse switch subsequent to closure of said interlock switch and prior to movement of said trip lever into its issuer position.

9. An interlock unit for a race totalisator ticket issuer, comprising, an interlock lever able to assume either a locking position or an unlocking position, spring biasing means which influence said interlock lever to assume and remain in its locking position, a ticket issuer hand piece, means operable on depression of the ticket issuer handpiece to allow said interlock lever to assume its locking position and thereby hold said handpiece depressed, a thrust rod which is movable towards said interlock lever, a movable packing member able to assume a working position directly between said thrust rod and said interlock lever, a lever having said packing member mounted thereon, a trip lever able to assume either an integrator position or an issuer position, spring biasing means which influence said trip lever to assume and remain in its issuer position, spring biasing means for keeping said packing member lever in touch with said trip lever, an interlock switch which is closed by said interlock lever when in its locking position, a trip magnet in series with said interlock switch, a spring-biased escapement lever in armature relation to said trip magnet, an escapement wheel in

operative association with said escapement lever, a motor spring for said escapement wheel, a pair of multi-impulse contacts in series with said interlock switch, means enabling repetitive opening and closing of said multi-impulse switch in consonance with step-by-step rotation of said escapement wheel, a single throw cam fixed relative to said escapement wheel, a spring-biased follower lever which is associated with said single-throw cam and is engageable with said trip lever to define the integrator and issuer positions thereof, a pair of self-opening integrator contacts which are in series with said interlock switch and are closed by said trip lever when in its integrator position, a pair of self-opening issuer contacts which are closed by said trip lever when in its issuer position, and cam and follower devices which on closure of said issuer contacts place said interlock lever in its unlocking position and then place said trip lever in its integrator position.

10. An interlock unit for a race totalisator ticket issuer, comprising, an interlock lever, a biasing spring for said interlock lever, an initiating lever having a stepped portion engageable with said interlock lever, a ticket issuer hand piece, a dropper connected to said initiating lever and to the ticket issuer handpiece, a spring-biased thrust rod movable towards said interlock lever, a packing member able to lie between said thrust rod and said interlock lever, a spring-biased lever whereon said packing member is mounted, an interlock switch closable by said interlock lever, a trip magnet in series with said interlock switch, a spring-biased escapement lever in armature relation to said trip magnet, an escapement wheel in operative association with said escapement lever, a motor spring for said escapement wheel, a cam which is fixed to said escapement wheel and has the same number of throws as said escapement wheel has teeth, a self opening multi-impulse switch connected in series with said interlock switch and in follower relationship with said cam, a single throw cam fixed relative to said escapement wheel, a spring-biased follower lever which is associated with said single-throw cam, a spring-biased trip lever engageable with a stepped portion of said follower lever and with said packing member lever, a pair of integrator contacts in series with said interlock switch and a pair of issuer contacts alternatively closable by said trip lever, two follower blocks respectively mounted on said interlock lever and said trip lever, two release cams respectively associated with said follower blocks, and means operable in response to closure of said issuer contacts for turning said release cams.

AWDRY FRANCIS JULIUS,
EVA DRONGHSIA ODIERNA JULIUS,
AWDRY FRANCIS JULIUS,
RUSSELL STUART HICKS,
*Executors of the Estate of George Alfred Julius,
Deceased.*
